DESIGN FOR A HAIR ORNAMENT

Leo J. Gagnon, Leominster, Mass., assignor to Fosgood Corporation, Leominster, Mass., a corporation of Massachusetts

Application July 16, 1938, Serial No. 78,545

Term of patent 7 years

To all whom it may concern:

Be it known that I, Leo J. Gagnon, a citizen of the United States and resident of the city of Leominster, in the county of Worcester and State of Massachusetts, have invented a new, original, and ornamental Design for a Hair Ornament, of which the following is a specification; reference being had to the accompanying drawing, forming part thereof, in which:

Figure 1 is a front view of a hair ornament embodying my new design.

Fig. 2 is a top plan view thereof.

The dominant features of my design reside in the portions shown in full lines.

I claim:

The ornamental design for a hair ornament substantially as shown and described.

LEO J. GAGNON.
